(57) **CLAIM**

The ornamental design for a carrier with an aperture for a beverage-dispensing spout as shown and described.

DESCRIPTION

FIG. 1 is a left-rear perspective view of the carrier with an aperture for a beverage-dispensing spout, showing my new design.

FIG. 2 is a front view of the carrier with an aperture for a beverage-dispensing spout of FIG. 1.

FIG. 3 is a right view of the carrier with an aperture for a beverage-dispensing spout of FIG. 1.

FIG. 4 is a rear view of the carrier with an aperture for a beverage-dispensing spout of FIG. 1.

FIG. 5 is a left view of the carrier with an aperture for a beverage-dispensing spout of FIG. 1.

FIG. 6 is a top view of the carrier with an aperture for a beverage-dispensing spout of FIG. 1.

FIG. 7 is a bottom view of the carrier with an aperture for a beverage-dispensing spout of FIG. 1.

FIG. 8 is a left-rear perspective view of the carrier with an aperture for a beverage-dispensing spout of FIG. 1; and, FIG. 9 is a cross-sectional view along the line 9-9 in FIG. 5. The broken lines shown represent environmental subject matter and form no part of the claimed design.
